INTERNAL-COMBUSTION ENGINE WITH DEMOUNTABLE POWER UNITS

Raymond W. Kronlund, Tacoma, Wash.

Application September 4, 1945, Serial No. 614,324

7 Claims. (Cl. 121—117)

(Granted under the act of March 3, 1883, as
amended April 30, 1928; 370 O. G. 757)

1

This invention relates to internal combustion engines and is illustrated herein as embodied in a two-cycle, radial, Diesel type of engine.

It is an object of the present invention to provide a radial type of internal combustion engine in which each cylinder and piston has its own individual crankshaft and comprises a separate, independent power unit that is independently mounted on the engine housing and detachably interconnected with the transmission gearing therein whereby the units may be each demounted separately without disturbance to the remainder of the assembly.

Another object of the invention is to provide a simple, compact, power transmission assembly incorporating balancing flywheels as a part of the gearing thereof.

A further object of the invention is to provide in an engine of this character, a design and construction that readily lends itself to the use of radially disposed cylinders in either single or dual banks depending upon power output requirements and in which, in either event, the firing order is so arranged as to give a maximum balanced performance with a minimum of vibration.

With the above and other objects and features in view, the invention will now be described with reference to the accompanying drawings which illustrate a preferred embodiment of the invention and will be pointed out in the claims.

In the drawings:

Fig. 1 is a sectional side elevation of the improved internal combustion engine illustrating the cylinders and transmission in a dual bank assembly;

Fig. 2 is a sectional end elevation of one of the banks of cylinders taken on the line II—II of Fig. 1;

Fig. 3 is a sectional elevation taken on the line III—III of Fig. 1 and showing a section of the power transmission gearing; and

Fig. 4 is a sectional elevation taken on the line IV—IV of Fig. 1 showing another section of the power transmission gearing and its connection with the driven shaft of the engine.

The invention is shown herein in an engine embodying dual banks of eight cylinders each. It will be understood, however, that the number of cylinders may be reduced and that a single bank of eight cylinders, or less, only may be employed.

The casing or housing is comprised of two sections 10 and 12. Each section is formed octagonally toward its outer end to provide eight angularly disposed bosses 14 upon which the cylinder power units 16 are mounted. At their inner ends the sections have circumferential flanges 18 by means of which they are secured together by studs such as 20, a suitable gasket being first inserted between the flanges, to insure

2

a tight joint. End plates 22 and 24 are secured to the outer ends of the housings 10 and 12, respectively. The end plates carry inwardly projecting bearings 26 and 28 in which a horizontally disposed main shaft 30 is rotatably mounted.

Oppositely disposed frame members 32 and 34 of circular shape are fitted within the inner ends of the housings 10 and 12 and are secured by bolts 36. The members 32 and 34 are internally recessed so that, when the members are assembled together as shown in Fig. 1, they form a compartment 38 for enclosing certain of the gears of the transmission which is to be later described. Bearings 40 and 42 are fixed centrally in each of the frame members for receiving and further supporting the main shaft 30. By the provision of the members 32 and 34 the entire housing assembly is integrated, strengthened and reinforced to withstand stresses developed by the power cylinder units 16 now to be described.

Referring to Fig. 2, each power unit 16 comprises a cylinder block 44 having a series of the usual annular cooling fins 46 externally thereof. The usual hardened sleeve insert 48 is mounted within the bore 50 to receive the piston 52. The head 54 of the cylinder is secured thereon by studs 56. The lower end of the block 44 is cut away on opposite sides as at 58 thus forming two diametrically opposite depending supports 60 and 30 at the same time providing clearance for the rotation of a crankshaft 63. The lower ends of the supports 60 are provided with semi-cylindrical bearing recesses 62 for receiving the opposite ends of the crank-shaft 63. The bearings for the shaft are completed by a pair of separate cap members 64 having complementary semi-cylindrical bearing recesses 66. The members 64 are secured in position to rotatably support the crankshaft by four, long, tie bolts 68 that extend through the head 54, spaced bores provided in the cylinder block 44 and the depending supports 60 thereof, and through openings in each side of the cap members 64.

In this manner the extremities of the unit i. e., the head 54 and the cap members 64 are rigidly interconnected with the body of the cylinder to withstand high pressures.

The piston 52 has a wrist pin 70 that is connected in the usual manner by a piston rod 72 with a crankshaft 63. Each cylinder block 44 has integrally formed therewith an external annular flange 74 disposed at an angle thereon corresponding to the angle of the mounting bosses 14 formed on the housings 10 and 12, the lower end of the flange being substantially even with the lower end of the cylinder. The cylinder units 16 are mounted on the housings by inserting their lower ends through openings 73 provided in the bosses 14 and seating the flanges 74 thereupon by shifting the unit laterally, suitable gaskets

being interposed therebetween to insure a tight joint. Studs 76 passing through the flanges 74 and threaded into the bosses are set up to rigidly hold the units in mounted position.

Since each crankshaft 63 is individually mounted on its respective cylinder unit 16 as above described, if it becomes necessary to demount a particular cylinder for repair, replacement of parts, or other reasons, this may be readily accomplished without disturbance to the remainder of the assembly by simply removing the studs 76 of the cylinder and withdrawing that cylinder and its crankshaft as a unit, bodily, from the housing. By this arrangement and construction complete disassembly of the engine, such as has generally hitherto been necessary, is obviated.

Each crankshaft 63 has its inner end projecting beyond its inner set of bearings 62-66 (Fig. 1) and supporting a gear 78 secured thereon for meshing engagement with the transmission train now to be described.

The gears 78 are arranged to mesh with internal gear teeth 80 provided in the outer faces of flywheels 82. The flywheels 82 are rotatably mounted by means of bearings 84 on the main shaft 30. Collars 86 secured to shaft 30 retain the flywheels in proper lateral position thereon. The inner faces of flywheels 82 are also provided with internal gear teeth 88 (see also Fig. 3). Three sets of oppositely disposed gears 90 are fixed on the opposite ends of three separate stub shafts 92 extending through the compartment 38. Shafts 92 (Fig. 4) are spaced 120° apart about shaft 30 and are each journaled adjacent to their opposite ends in bearings provided in the side-walls of the compartment 38.

Within compartment 38, centrally of and to each shaft 92, there is keyed a gear 94. Each of the gears 94 are of equal diameter and each meshes with a common driven gear 96 keyed to the main shaft 30, thus completing the train of transmission gearing from the cylinder units 16 to the main shaft 30.

In operation, as the cylinders fire, the crankshafts 63 drive the gears 78, to rotate the flywheels 82 which, through the train of gearing just described, drive the main shaft 30.

Referring to Fig. 2 the cylinder and piston power units are numbered clockwise from the top-most cylinder, 1 to 8, inclusive, for the purpose of specifying the preferred firing order.

In single bank engines the pistons 52 of cylinders 1 and 5 are at top dead center, pistons 52 of cylinders 2 and 6 are 90° in advance of top dead center, pistons 52 of cylinders 3 and 7 are at bottom dead center, pistons 52 of cylinders 4 and 8 are 90° after top dead center. This arrangement gives a firing order, seriatim, of 1 and 5-2 and 6-3 and 7- and 4 and 8.

In dual bank engines the firing order is seriatim as follows:

First Bank	Second Bank
1 and 5 simultaneously with.....	3 and 7
2 and 6 simultaneously with.....	4 and 8
3 and 7 simultaneously with.....	1 and 5
4 and 8 simultaneously with.....	2 and 6

This firing order gives a constant, balanced imparting of power to the main shaft 30 and tends toward reducing vibration and an even distribution of pressure on the bearing surfaces.

It is noted that the points at which the gears 78 mesh with the internal gear teeth 80 are so disposed with respect to the angular openings 73

in the bosses 14 that the gears 78 may be readily slid laterally into mesh with the teeth 80 when a cylinder unit 16 is being mounted or as readily slid out of mesh with the teeth when a cylinder unit is being demounted.

The intake and exhaust ports for the cylinder units are indicated in Fig. 2 at 98 and 100, respectively. These are connected in the usual manner to suitable manifolds of conventional design and construction.

The cylinder heads 54 are each provided with a precombustion chamber such as is indicated at 101 in Fig. 1 and are connected by fuel lines (not shown) to a conventional fuel injection system including a pump indicated at 102. The pump may be driven by a ring gear 104 secured on the periphery of the right-hand flywheel 82 meshing with a pinion 106.

The invention described herein may be manufactured and used by or for the Government of the United States of America for Government purposes without the payment of any royalty thereon or therefor.

Having described the invention, what is claimed as novel and desired to be protected by Letters Patent of the United States is:

1. In a radial type of internal combustion engine having a plurality of cylinder-piston power units and a central drive shaft positioned therein, a transmission gearing train comprising, a flywheel having oppositely disposed faces mounted on said drive shaft in rotatable relation therewith, said flywheel having integral first and second internal circumferential gear means formed in said opposite faces thereof, third gear means associated with each of said plurality of power units, each of said third gear means being meshed with said first gear means on said flywheel, and fourth gear means secured to said drive shaft, said second gear means of said flywheel being geared to said fourth gear means.

2. A radial type internal combustion engine comprising a housing, a plurality of cylinder-piston power units each having an individual crankshaft mounted thereon, said power units being removably mounted on said housing, a drive shaft centrally located within said housing, a flywheel having oppositely disposed faces mounted on said drive shaft and relatively rotatable thereto, said flywheel having integral first and second internal circumferential gear means formed in said opposite faces thereof, a pinion gear attached to each of said crankshafts of said power units, each of said pinion gears being engaged with said first gear means of said flywheel, a plurality of idler shafts rotatably journaled within said housing and disposed parallel to said drive shaft, third and fourth gear means secured to said idler shafts, said third gear means being engaged with said second gear means of said flywheel, and a gear secured to said drive shaft and engaged with said fourth gear means.

3. A dual-bank radial type internal combustion engine including a central drive shaft common to both banks and having a bull gear secured thereto, each bank comprising a housing of substantially conical shape, a plurality of cylinder-piston power units removably mounted on said housing, said power units each having an individual crankshaft with a pinion gear secured thereto, a flywheel having oppositely disposed faces mounted on said drive shaft and relatively rotatable thereto, said flywheel having integral first and second internal circumferential gear means formed in said opposite faces thereof, each of said pinion gears being engaged with said first

gear means, three stub shafts equally spaced circumferentially and rotatably journalled within said housing, said shafts being disposed parallel to said drive shaft, and third and fourth gear means secured to each of said stub shafts, each of said third gear means being engaged with said second gear means of said flywheel, and each of said fourth gear means being engaged with said bull gear on said drive shaft.

4. A power unit for an internal combustion engine having a pyramidal housing with transmission gearing therein, said unit comprising a cylinder, a piston reciprocably mounted therein, a crankshaft rotatably journalled in the wall of said cylinder, a rod connecting said piston and said crankshaft, an annular flange mounted externally of said cylinder and integral therewith, the plane of said flange being disposed obliquely of the axis of said cylinder, said flange being adapted for removable attachment on an oblique face of said pyramidal housing, and a pinion gear on said crankshaft adapted for removable interconnection with said transmission gearing.

5. In a radial type of internal combustion engine, a housing of pyramidal shape providing a plurality of obliquely disposed faces, each of said faces having an opening therein, a central drive shaft positioned within said housing and coincident with the longitudinal axis of said pyramidal housing, a plurality of power units each comprising a cylinder, a piston reciprocably mounted in said cylinder, a crankshaft rotatably journalled in brackets which form integral extensions on the lower end of said cylinder, a rod connecting said piston and said crankshaft, and an annular flange mounted externally of said cylinder, the plane of said flange being disposed obliquely of the axis of said cylinder and near the lower end thereof, the lower end of said cylinder being inserted in one of said openings in said faces whereby said annular flange is removably positioned on an oblique face of said housing and the axis of said cylinder is normal to the axis of said drive shaft and the axis of said crankshaft is parallel to said drive shaft.

6. A power unit for an internal combustion engine having a pyramidal housing with trans-

mission gearing therein, said unit comprising a cylinder, a crankshaft rotatably journalled in the wall of said cylinder, a piston reciprocably mounted in said cylinder and operably connected to said crankshaft, an annular flange mounted externally of said cylinder and integral therewith, the plane of said flange being disposed obliquely of the axis of said cylinder, said flange being adapted for removable attachment on an oblique face of said housing, and a pinion gear secured to said crankshaft.

7. In a radial type of internal combustion engine, a housing formed with a plurality of obliquely disposed faces, each of said faces having an opening therein, a drive shaft positioned within said housing and coincident with the longitudinal axis of said housing, a plurality of power units each comprising a cylinder having a piston reciprocably mounted therein, a crankshaft rotatably journalled in the wall of said cylinder near one end thereof, means operably connecting said piston to said crankshaft, and an annular flange mounted externally of said cylinder and integral therewith, the plane of said flange being disposed obliquely to the axis of said cylinder, the said one end of said cylinder being inserted in one of said openings in said faces whereby said flange is removably positioned on an oblique face of said housing and the axis of said cylinder is normal to the axis of said drive shaft and the axis of said crankshaft is parallel to said drive shaft.
